UNITED STATES PATENT OFFICE.

GEORGE CORBETT, OF NEW YORK, N. Y., ASSIGNOR TO ALFRED S. BISHOP,
TRUSTEE, OF PITTSBURG, PENNSYLVANIA.

DESIGN FOR A BADGE.

SPECIFICATION forming part of Design No. 28,677, dated May 24, 1898.

Application filed March 21, 1898. Serial No. 674,684. Term of patent 3½ years.

To all whom it may concern:

Be it known that I, GEORGE CORBETT, a citizen of the United States, residing at New York, in the county of New York and State of New York, have invented a novel and original Design for Badges, of which the following is a full, clear, and exact description, reference being had to the accompanying drawing, forming part of this application, which represents a face view of the obverse side of a badge made in accordance with my design.

My design relates to badges or medals commemorative of the twenty-seventh triennial conclave Knights Templar of the United States of America, especially designed for use in the city of Pittsburg, Pennsylvania, and intended to be used as an emblem and souvenir indicative of the characteristic local industries, containing such characteristic elements, with the elements forming the insignia appropriate to the order.

The leading features of my design include a circular-shaped base 2, upon which and with which is incorporated, projecting upwardly and downwardly at each end, the encampment cross of Knights Templar 3, the middle cross bars of which extend to and touch the inner edge of an outer band 4. The cross 3 is surrounded by a band 5, and the base is provided with an inner annular band 6, which is interrupted by the cross-arms of cross 3.

Upon the center of the base, covering the middle portion of cross 3, is a cross of Malta 7, interspersed between the points of which are the rays of a sunburst 8. An inner circle 35 9, of reduced diameter, is mounted centrally upon the cross of Malta, representing the seal of the grand encampment and furnished with the figure of a knight with a drawn sword. This seal is surrounded by a circle 40 10, in the bottom of which is the figure of a Maltese cross. The main body portion of the badge as thus described is pendent by two chains 11 11 from an ornamental bar 12, surrounded by a semicircular scroll 13.

Beneath the scroll upon the bar 12 are the raised figures of a Templar's mace 14 and sword 15, upon which rests a keystone 16, surrounded in the center by the coat of arms of the State of Pennsylvania 17.

Upon the base, crosses, rings, or scrolls, or either of them, any suitable words, numerals, legends, or emblems may be displayed.

What I claim is—

The design for a badge herein shown and 55 described.

In testimony whereof I have hereunto set my hand.

GEORGE CORBETT.
